ACTIVATION DEVICE FOR THE HELIO-PYRETIC TREATMENT OF MATTER

Maximilian L. Herzig and Frances R. Herzig,
Puyallup, Wash.

Application November 16, 1936, Serial No. 111,102

3 Claims. (Cl. 128—395)

This invention relates to the irradiation of fluids and suspensions and especially those intended for medicinal use in the practice of the healing art.

The objects of the invention are to provide means for exposing the material being treated to the desired rays from the sun or from any artificial source of visible or invisible rays; to provide means whereby the exposed area may be controlled; to provide means whereby the active rays are concentrated upon the material being treated; to provide means whereby a plurality of liquids may be simultaneously treated with the same degree of radiation; to provide means for promoting the fluorescence, phosphorescence and luminescence of the materials being treated and to provide means for secondary radiation; to provide means whereby the time of exposure of the fluid to the rays may be shortened without correspondingly decreasing the radio-activity of the substance; and to provide for heating the substance simultaneously with its exposure to the rays from the source of radiation.

We attain these and other objects by the devices and arrangements illustrated in the accompanying drawing, in which—

Fig. 1 is a front elevation of my device; Fig. 2 is a vertical cross-section thereof; Fig. 3 is a plan view thereof, a portion being broken away to reveal the interior thereof; Fig. 4 is a rear sectional view thereof, taken in the line 4—4 in Fig. 2; Fig. 5 is a vertical section taken on the line 5—5 in Fig. 6, showing a variation of my device; Fig. 6 is a front elevation thereof; and Figs. 7 and 8 show variations in the form of header.

Similar numerals of reference refer to similar parts throughout the several views.

It is a well known fact that heat energizes and activates living forms and tissues and synergizes the processes of metabolism, and that cold inhibits growth in living organisms and retards healing and renders dormant the vital processes. It is also well known that certain rays of the visible and invisible spectrum have bactericidal powers, while certain other rays, or similar rays with different conditions of exposure, can be made to proliferate growth of tissue, enhance development and metabolism, and again other rays, such as the deep X-rays destroy certain living forms and vagabond cells.

It has been usual to pass the fluid to be irradiated in passageways or containers around the source of the rays thereby producing more or less turbulence in the fluid. This is particularly an unnatural agitation in the case of blood, because

blood does not normally circulate in a turbulent manner but in a smooth and even flow. It is important that a device of this character should be adapted for use with blood and blood mixtures because the body can be vitalized and caused to be activated, as by certain vitamins, by the expedient of proper irradiation of blood with certain radio-active and/or photosensitive substances, as per example a greater calcium and phosphorus balance may be obtained by the irradiation of the substance known as sterol, in the blood. In addition to their bactericidal and antitoxic potency, certain rays, in proper dosage, may be made to increase the leucocytes, so called policemen of the blood, as well as the red cells with the accompanying sense of well-being and fortification against infection, which benefits are passed on to the remote fluid and fixed cells and tissues within reach of the circulation.

Our device may also be used in conjunction with diagnostic procedures such as rendering the gall bladder more visible by X-raying the organ following the injection of appropriately treated material indicated.

This device may be used for blood and blood mixtures either by the direct and closed or the indirect and open method.

The fluid being irradiated may pass through the device several times in series, if it is desired to give it a very prolonged exposure to the rays, or it may pass through the device in several parallel streams if a greater speed of irradiation is desired.

Referring, now, to the drawing, it will be seen that the frame comprises a flat plate 1, having rearward-extending flanges 2 and a central opening 3. The space to the rear of the plate 1 is occupied first by a series of quartz tubes 4 which lie across the opening 3 in the plate 1 and each of which is adapted to receive and convey a stream of the fluid to be treated by the radio-active rays passing through the opening 3 in the plate 1. In certain cases we also expose the said tubes 4 to radio-active rays from the rear as well as through the opening 3, thereby increasing the exposure thereto and reducing the time necessary to attain a given degree of irradiation. In other cases we expose the rear sides of said tubes 4 to heat. In this case the source of heat is mounted in the chamber 5 to the rear of the said tubes 4 and is preferably mounted on an adjustable frame 6 whereby its distance from the said tubes 4 may be adjusted. In still other instances we mount a small arc light 7 on the said adjustable frame 6, said light being the

source of heat and a great variety of radio-active rays.

When it is not desired to utilize the above described rear treatment, we provide a reflecting surface in the frame 1 to the rear of said quartz tubes 4. As shown in Fig. 3, the side flanges 2 are provided with grooves 8 and a curved and corrugated polished metal plate 9 is slid between the said grooves 8. This plate 9 is formed substantially as shown in Fig. 3, having a general cylindrically curved form and having parallel grooves 10 of much shorter radii forming depressions substantially concentric with the said tubes 4. This mirror plate 9 therefore receives the radiation which has passed between and through the tubes 4 and reflects it back on to the said tubes, thus utilizing the radiation to a fuller extent than without the use of said reflector.

20 The tubes 4 pass through holes 11 in the upper and lower flanges 2 of the plate 1 and are held in place therein by means of rubber gaskets or washers 12, as shown in Fig. 2. They can therefore be easily removed from the frame for the purpose of sterilization or renewal as desired. Both ends of each tube 4 are connected to the headers 13 by means of rubber tubing 14. A variety of such headers may be provided, as illustrated in Figs. 7 and 8 in the drawing. In 25 Fig. 7 the fluid will pass in series from one to the other tube so that the stream will be successively exposed in each of the said tubes 4; or in Fig. 1 it will pass in parallel through the several tubes, the stream of fluid being divided into a 30 number of smaller streams, each of which is simultaneously and equally exposed to the radioactive influence; or in Fig. 8 the tubes may be separately attached to different supplies of different fluids which will simultaneously pass 35 through the device in different tubes.

In the variation of the above described apparatus, shown in Figs. 5 and 6, the stream of fluid passes by one of the several entrance passages 15 into a chamber 16 formed in a metal casing 17. The metal casing has an opening 18 in its front, said opening being closed by means of a quartz lens or sheet 19, held in place by a screw ring 20, or other similar means; a suitable washer 21 being provided to prevent leakage of the fluid past the quartz lens 19. The rear of the chamber 16 is formed concave and is highly polished to form a reflective surface 22. A suitable outlet passage 23 permits the fluid to pass from the chamber 16. In order 40 to heat the fluid in the chamber 16, we form a second closed chamber 24 to the rear of the rear reflective surface 22 and mount in said chamber 45 24 a suitable source of heat, such as an electric resistance unit 25. Suitable ventilating passages 26 may be provided at the upper and lower ends of this heat chamber 24. The chamber 16 may also be used to mix different fluids entering it by the several passages 15 at the same time 50 that they are being heated and irradiated.

60 When it is desired to control the area of exposure of the liquid being treated, we attach an adjustable iris thereto, said iris having a plurality of shutters 27 operable in a manner similar to the adjustable iris found in the usual photographic camera.

In certain cases the fluid is caused to flow through the device by means of pressure developed by other means than by gravity.

70 In the case where the arc light is used as above

described, and in which certain forms of carbons are used, gases are given off which would contaminate the surface of the tubes 4 by condensing metallic oxides thereon, thereby rendering them less effective for the transmission of the desired rays, we convey a washing fluid, preferably distilled water, by the pipes 28 to each of the tubes 4 below the upper flange 2 of the frame 1, and permit it to flow down the outside of the tube, thus carrying away any oxides which may condense thereon and keeping the quartz tubes clean.

Our device may be used in any position, horizontal, vertical or inclined, so long as the fluid level of the upper end is above the outlet end thereof or so long as suitable pressure is applied to the fluid. This is not possible when a mercury light is attached to the irradiating container because the light must be kept in vertical position while in use.

An unique and it is thought original mode of treatment is provided by the use of our invention in that the beneficent effects of an artificial fever of any predetermined degree may be imposed upon a small portion of the circulation of the blood, or as much thereof as may be indicated, thereafter to be returned to the circulation for a similar and beneficent impetus upon the rest of the body economy.

Other advantages of our invention are that it provides means whereby the blood, in a transfusion operation, may be kept at body temperature; and means whereby fluids may be submitted to pasteurizing or other degrees of heat while in process of irradiation.

It will be understood that the term "radio-active" herein applies to radiations covering the visible and invisible spectrum.

From the above description, it will be seen that a fluid in passing through the tubes 4 may be exposed to any degree of radio-active influence, and any desired degree of heat simultaneously and that the rate of the flow of the fluid may be changed by causing it to flow in parallel or in series through the several tubes and that the adjustable iris, which may also be applied to the form shown in Figs. 5 and 6, adjusts the area of exposure of the fluid in the tubes 4 or in the chamber 16.

It will be understood that many variations in the form, construction, and arrangement of the parts of our device may be made without departing from the spirit of our invention as outlined in the appended claims.

Having, therefore described our invention, what we claim and desire to secure by Letters Patent, is:

1. In a device for exposing a fluid to radio-active influence, the combination with a frame; a plurality of parallel radio-active penetrable tubes mounted in said frame and adapted to convey the fluid to be treated across the field of radio-active rays; and a reflector adjustably and removably mounted in said frame and comprising a polished metal plate of general cylindrical form with corrugations therein.

2. A device as set forth in claim 1, wherein said corrugations are substantially concentric with said tubes.

3. A device as set forth in claim 1, wherein said cylindrical curve and said corrugations have axes parallel with said tubes.
